REGULATOR ADJUSTMENT FOR WATCHES
AND OTHER HOROLOGICAL INSTRUMENTS

Henry Line, Carlisle, Pa.

Application May 10, 1951, Serial No. 225,631

12 Claims. (Cl. 58—113)

1

My invention relates to new and useful improvements in horological instruments and more particularly to regulators for watches and the like, the primary object of the invention being to provide an adjustment for the regulator which may be quickly and readily actuated to overcome the many difficulties now encountered in the regulating of watches with conventional regulating means.

It is a known fact that the oscillations of a watch balance are not strictly isochronous and the periodic time varies more or less with amplitude. However, it is not practicable to obtain a constant amplitude, since this depends, for example, on changes of position of the watch which cause changes of friction. The variation of the force exerted by the main spring will also cause variations of the amplitude of the balance throughout the day's run and, furthermore, the amplitude of oscillation diminishes over long periods of time as the viscosity of the oil changes. In other words, a variety of factors affect the amplitude of the balance of a watch. Therefore, it will be seen that it is not possible to have oscillations of constant amplitude and it is necessary to reduce as far as possible the influence of amplitude on the rate of the watch.

It has long been known that a considerable part of the departure from isochronism is due to the clearance between the pins on the regulator, or the one pin and the boot of the regulator. This clearance is necessary to insure that the spring is not damaged when the regulator is moved. It would be possible, under certain circumstances, to eliminate the pins, but if this is done, the possibility of easy adjustment of the rate of the watch is removed. For instance, to correct the rate of a watch without using the regulator, that is, without changing the effective length of the balance spring, it would be necessary to adjust the moment of inertia of the balance. There are many problems involved in such a construction and the method of adjusting under such circumstances would be unpopular with repairmen who prefer the regulator, regardless of its evils, since it is a practical means of changing the rate of a watch.

It is also a well known fact that the clearance of the spring between the pins, or the curb pin and boot of the regulator, has considerable bearing on the performance as regards isochronism. The fact that the spring wire is not gripped is the most serious defect of the normal regulator, since it renders it impossible to obtain a stable rate. Furthermore, after a watch has been oper-

2

ationally set for an appreciable period of time, the pins and spring may acquire a certain accumulation of moisture and/or lubricant oil, which results in an appreciable physical change in the relationship of the elements one to the other, causing a variation in the resilient rebound induced in the balance wheel. Obviously, this results in a changing of the timing of the watch. This uncertain element of maladjustment in the tension of the spring makes positive compensatory regulation unfeasible. This results under normal conditions in a hit or miss adjustment being made which, in most instances, will not regulate the watch sufficiently to satisfy the owner or user even for a short time.

My invention contemplates a new and improved structure, including an adjustable element in substitution for one of the conventional stationary pins which has a distinct and definite movement of predetermined travel when manually actuated by the operator. This element is so designed with a head to rock or oscillate on the regulator arrow and capable of being retained in an adjusted position by a resilient pressure on the head thereof. This element co-operates with the other pin or the boot of the regulator to bind the spring and cause the necessary variation in its tension, thus making the desired timing adjustment.

It is, therefore, an object of this invention to provide a new and improved regulator mechanism for watches, and the like, which will avoid the various disadvantages and limitations of the present day known mechanisms.

A further object of the invention is to provide a new and improved regulator mechanism which will enable a more positive adjustment to be made in the timing than is possible under the conventional construction.

A further object of the invention is to provide a new and improved regulator mechanism which will not be materially affected by moisture and vapors ordinarily arising from watch movements and settling on the mechanism to affect the timing thereof.

A still further object resides in providing pins, one of which is capable of movement with respect to the other to bring the spring in contact therewith without interfering with the effective functioning thereof.

A still further object resides in providing a new and improved regulator mechanism which is simple and durable in construction, inexpensive to manufacture and one which will be very efficient and useful in operation.

With these and numerous other objects in view, my invention consists in the novel features of construction, combination and arrangement of parts, as will be hereinafter referred to and more particularly pointed out in the specification and claims.

In the accompanying drawing, forming a part of this application,

Figure 1 is a general top view of a regulator mechanism embodying this invention;

Figure 2 is a sectional elevation, as seen on line 2—2 of Figure 1, with the movable tension pin in closed position;

Figure 3 is a view similar to Figure 2, with the tension pin in open position;

Figure 4 is a sectional detail on line 4—4 of Figure 3, of the pressure spring used in this embodiment;

Figure 5 is a sectional view, taken on line 5—5 of Figure 2, of the pressure spring with the tension pin in position;

Figure 6 is a top plan view of the pressure spring;

Figure 7 is a side elevation of the tension pin in elevation;

Figure 8 is a view in elevation taken at right angles to Figure 7;

Figure 9 is a detail to show the pressure and stationary pins in a position to bind the hair spring used in the mechanism on line 9—9 of Figure 2;

Figure 10 is a view in perspective of the regulator arm modified to hold the tension pin; and

Figure 11 is a perspective detail of the head of the tension pin showing its underside particularly.

In the drawing, similar reference characters designate similar parts throughout the various views and this drawing illustrates a complete regulator mechanism. In a general way, the structure here shown includes the components shown and described in my Patent No. 2,482,351, issued September 20, 1949.

The structure includes a balance bridge 1, a balance wheel 3, and a hair spring 4. The jewel plate 6, which positions the bearing jewel 7 in place, is secured in position by the screws 5. The jewel plate is encompassed by a conventional regulator ring 13 which is split as shown at 14. The regulator arrow or indicator arm 15 extends from the ring 13 and diametrically opposite the arm 15 is the short arm 16 which has projecting downwardly therefrom the pin or boot 17. One of the most important features of my invention, namely, an adjustable pin or the like, referred to in the drawing generally by the numeral 20, is supported on the arm 16 and projected through a rectangular slot 21 arranged longitudinally in the arm 16 adjacent its outer end. The slot 21 is intersected by the grooves or slots 22 in the upper face of the arm 16, extending transversely of the latter and said grooves or slots 22 are substantially U-shaped in cross section, as best seen in Figure 10 of the drawing.

This member 20 includes a circular head 23 having its upper surface 26 bevelled from two edges and converging in a central ridge or the like 25 extending diametrically of said head, as shown in Figures 7 and 8. The under face of the head 23 is flat and has a lug 29 extending diametrically thereof, said lug being semi-circular in cross section and adapted to fit in the grooves 22 of the arm 16. Projecting from the head 23 between the lugs 29 is the pin 27 which is substantially the same length as the stationary pin

or boot 17, the lower end of said pin being slightly curved, as best seen in Figures 2, 3 and 7. As stated above, the pin is projected through the slot 21 so that the lugs 29 fit in the grooves 22 permitting the pin to be rocked or oscillated on the arm 16. When the pin is moved in one direction, as shown in Figure 2, the lower end of the pin 27 will be substantially parallel with the pin 17 and engage the outer convolution of the spring 4. When the pin is rocked in the opposite direction, the pin 27 will be disengaged from the spring 4, as shown in Figure 3 of the drawing.

The pin 27 is retained in its various positions when moved thereto by the frictional resistance induced by a pressure spring 24 against one of the converging faces 26 of the head 23, as best shown in Figures 2 and 3 of the drawing. This pressure spring 24 is shown disconnected in Figure 6 of the drawing and is shown to be relatively thin and flat, with two rectangular slots 30 and 31 in spaced longitudinal alignment. The one end of said spring 24 is curved or hooked, as shown at 32 and adapted to contact the head 23, that is, either on one face or the other of the bevelled faces 26. This spring 24 is held in position on the regulator ring 13 through the medium of a head 33 or a stud 34 extending through the slot 30. The T-head 33 is set transversely and the spring 24 can be fastened in position by aligning the slot with said head and turning the spring to a 90 degree angle to retain the spring under said head, as shown in Figure 4. The slot 31 is brought into alignment with an upstanding stud 35 carried on said regulator ring and acts as a guide for said spring in its movement with respect to the regulator mechanism. The spring 24 when in position, as shown in Figures 2 and 3, is under tension so that the resiliency thereof may properly affect the moveable or adjustable pin.

To operate the mechanism, adjustment of the regulator is accomplished first by moving the leaf-spring 24 to the right, as shown in Figure 3, so that the curved end 32 will ride over the head 20 of the moveable pin to contact the one bevelled face 26 so that said pin 27 will be moved away from the pin or boot 17 and out of contact with the convolution of the hair spring 4. After this has been accomplished, the indicator arm 15 is moved in whichever direction desired to the approximate position determined to suit the timing required. Finally, the spring 24 is moved to the left, as shown in Figure 2, so that the curved end 32 of said spring will ride over the ridge 25 of the head 23 and rock the pin on its bearings so that said pin 27 will contact the spring 4 and substantially retain the latter in contact with the pin or boot 17. Additional adjustments, if and when necessary, can be accomplished by repeating the above procedure as often as required until correct timing is attained. In either position, as shown in Figures 2 and 3, the pin 27 is resiliently held firmly by the spring 24 and in order to assist in the movement of the spring 24 with respect to the other elements, the notches 28 are provided in the side edges thereof which will receive therein portions of an instrument in the fingers of the operator.

From the foregoing description of my improved regulator, the method of applying same to use will be readily understood and it will be seen that I have provided a comparatively simple, inexpensive and efficient means for carrying out the various objects of the invention. With this structure, there may be accuracy of performance,

stability of rate, ease and rapidity of adjustment, safety of the hair spring and ease of operation.

While I have particularly described the elements best adapted to perform the various functions set forth, it is apparent that various changes in form, proportion and in the minor details of construction may be resorted to, without departing from the spirit or sacrificing any of the principles of the invention.

What is claimed is:

1. In a horological regulator mechanism including a regulator indicator arm, a balance wheel and a hair spring for controlling the operation of the whole, an auxiliary regulating mechanism comprising a pin means mounted on said arm and extending into the plane of said spring, and a member freely removable and oscillatingly mounted on said arm adjacent to said pin means and adapted to be moved through a predetermined amount of travel to co-operatively hold said spring in conjunction with said means.

2. In a horological regulator mechanism including a regulator indicator arm, a balance wheel and a hair spring for controlling the operation of the whole, an auxiliary regulating mechanism comprising a pin means mounted on said arm and extending into the plane of said spring, and a member freely removable and oscillatingly mounted on said arm adjacent to said pin means and adapted to be moved through a predetermined amount of travel to co-operatively hold said spring in conjunction with said means and means for locking said member in predetermined positions.

3. In a horological regulator mechanism including a regulator indicator arm, a balance wheel and a hair spring for controlling the operation of the whole, an auxiliary regulating mechanism comprising a stationary pin means mounted on said arm and extending into the plane of said spring, and a member freely removable and oscillatingly mounted on said arm adjacent to said pin means and adapted to be moved through a predetermined amount of travel to co-operatively hold said spring in conjunction with said means, and manually operable means for moving and locking said member in effective and ineffective positions with respect to said hair spring.

4. In a horological regulator mechanism including an indicator arm, ring, balance wheel and hair spring, a movable member adjustably mounted on said arm for rocking movement thereon and extending into the plane of said spring and arranged to engage and disengage a convolution of said hair spring as it is moved into different predetermined positions on said arm, and means for actuating and simultaneously resiliently holding said member in said positions.

5. In a horological regulator mechanism including an indicator arm, ring, balance wheel and hair spring, a movable member rockably mounted on said arm and extending into the plane of said spring and arranged to engage and disengage a convolution of said hair spring as it is moved into different predetermined positions on said arm and manually operable means for rocking and simultaneously resiliently holding said member in said positions.

6. In a horological regulator mechanism in-

cluding an indicator arm, ring, balance wheel and hair spring, a movable member adjustably mounted on said arm and extending into the plane of said spring and arranged to engage and disengage said hair spring as it is moved into different predetermined positions on said arm, and means for resiliently holding said member in said positions, said member being locked on said arm by said means and arranged for removal and replacement by re-aligning the means in relation thereto, said member including a head with a converging upper face portion and a lug on its underside, adapted to be located in a slot and groove arrangement provided therefor in said arm to permit the said positions to be derived by hingedly moving said member on its head against said spring.

7. In a horological regulator mechanism including an indicator arm, ring, balance wheel and hair spring, a fixed pin on said arm, a movable pin rockably seated on said arm and having a head thereon, and a slideable means on said arm having contact with the head of said movable pin to actuate the latter on said arm.

25 8. The device as set forth in claim 7 wherein the slideable means is a resilient member tending to resiliently retain the movable pin in predetermined adjusted positions.

9. The device as set forth in claim 7 wherein the head of the movable pin is dual faced, and the slideable means is a resilient member having a portion thereof adapted for contact with the faces of the head of the movable pin to actuate the latter and resiliently retain the same in predetermined adjusted positions.

30 10. A device as set forth in claim 7, wherein the head of the movable pin is dual faced, and the slideable means includes a flat spring having one end thereof adapted for contact with the faces on the head of said movable pin to resiliently retain said latter pin in predetermined adjusted positions.

11. In a horological regulator mechanism including an indicator arm, ring, balance wheel and hair spring, a fixed pin on said arm extending into the plane of said spring, and a second pin rockably seated on said arm adjacent said fixed pin and adapted to cooperate with the latter in its relation with the hair spring.

45 12. In a horological regulator mechanism including an indicator arm, ring, balance wheel and hair spring, a fixed pin on said arm extending into the plane of said spring, and a second pin rockably seated on said arm adjacent said fixed pin adapted to cooperate with the latter in its relation with the hair spring, and manually operable means for rocking the second pin on its seat.
